UNITED STATES PATENT OFFICE.

GEORGE W. BECHTEL, OF SPOKANE, WASHINGTON.

SWIMMING APPLIANCE.

1,342,619.

Specification of Letters Patent.

Patented June 8, 1920.

Application filed November 5, 1919. Serial No. 335,874.

To all whom it may concern:

Be it known that I, GEORGE W. BECHTEL, a citizen of the United States, residing at Spokane, in the county of Spokane and 5 State of Washington, have invented certain new and useful Improvements in Swimming Appliances, of which the following is a specification.

The present invention relates to an im- 10 proved swimming appliance designed for manual propulsion and capable of being steered both laterally and vertically whereby, in addition to the usual lateral steering, the appliance may be made to dive or de- 15 scend below the surface of the water, or ascend from below to the surface, at the will of the swimmer by proper manipulation of the required devices.

The primary object of the invention is 20 the provision of a buoyant swimming appliance for use primarily in the sport of swimming, but capable, also, of being used as a self propelled life-saving apparatus when needed, and the invention consists es- 25 sentially in certain novel combinations and arrangements of parts as illustrated in the drawings, and pointed out in the appended specification and claims.

In the accompanying drawings one com- 30 plete example of the physical embodiment of my invention is illustrated, the parts being combined and arranged according to the best mode I have so far devised for the practical application of the principles of the 35 invention.

Figure 1 is a side elevation of a swimming appliance built in accordance with the present invention and embodying the novel features thereof.

40 Fig. 2 is a top plan view of the appliance of Fig. 1.

Fig. 3 is an enlarged detail view of the operating gears for the propeller wheel, located preferably at the bow of the appliance, the housing and tubular casing for the 45 gearing and propeller shaft being shown in section.

Fig. 4 is an end view showing the crank casing or housing, and crank handles, together with one of the keel sections shown in dotted lines, to which the housing and 50 crank or gear case are attached.

Fig. 5 is a perspective view of the stern rudder for lateral steering of the appliance, showing also the foot operated tiller bar or 55 tiller that is pivoted on the adjustable post.

Fig. 6 is an enlarged, detail, sectional view at line 6-6 of Fig. 2, showing a lever for controlling one of the vertical rudders or 60 steering blades.

In the preferred form of the invention as illustrated in the drawings the appliance is adapted for use and propulsion by a single person, and consequently is sufficiently large to buoyantly support a swimmer, but is not 65 so large as to be cumbersome and difficult to handle or manipulate by the swimmer. The body of the appliance comprises a keel-board 1 extending fore and aft approximately the full length of the appliance, of 70 suitable wood and of proper dimensions for the convenience of the swimmer, while above the keel-board is a comparatively shorter deck board 2 secured to the keel-board amidships of the appliance and of 75 width to permit the swimmer to sit astride the deck or straddle the deck board and keel-board when in swimming position. Beneath the keelboard are two keel sections 3 and 4, the latter secured near the bow of 80 the appliance and the former nearer the stern, the forward ends or prows of these keel sections being sharpened as indicated in dotted lines in Fig. 2. The keel sections are of proper weight, size and material to perform the usual functions and stabilize the 85 appliance while afloat in the water, and are rigidly attached beneath the keel board as indicated in Figs. 1 and 2.

A pair of transversely arranged guide 90 braces 5 and 6 are provided on top of the deck board and are cut out or curved at 5' 6" to conform to the shape of the legs when the swimmer sits astride of the deck board between the forward fixed brace 5 and the 95 aft horizontally swiveled brace 6. The respective braces 5 and 6 are equipped with securing pins or bolts 7 and 8 passed downwardly through them, (the bolt 8 having a wing-nut 9) and through the longitudinally 100 extending central slot 10 in the deck board. Thus it will be seen that the braces or cross bars may be adjusted by the bolt and slot connection to suit the convenience of the

swimmer, and the aft brace 6 may be turned on its pivot 8 to accommodate the legs of the swimmer in their movements.

When propelling the appliance the swimmer straddles the deckboard and keel board between the two cross braces, then, facing toward the bow, where the propeller wheel 11 is located, leans forward and down, with his feet and legs to the rear in the posture 10 of a swimmer, and is ready to propel the appliance through the medium of the propeller wheel 11 and its shaft 12 by turning the two crank handles 13 and 14, on the ends of the transversely extending gear shaft 15, located beneath the keel board and keel sections in convenient position to be grasped by the two hands of the swimmer. The shaft 15 carries the large gear wheel or 15 driver 16 which meshes with the smaller pinion 17 on the countershaft 18 parallel with the driving shaft or crank shaft, and a bevel gear wheel 19 on this countershaft engaging with the bevel pinion 20 on the propeller shaft rotates the shaft to drive the propeller wheel 11 and propel the appliance. The propeller shaft extends longitudinally of the appliance beneath the forward keel section 4 and is supported therefrom in brackets 21, and a tubular casing 30 22 incloses the shaft, while the housing or gear case 23 conforming to the gear wheels within incloses the gears. Oil may be placed in the casing and housing to lubricate and reduce friction, and these parts will of course 35 be water tight to prevent egress of the oil and ingress of water. The housing and casing are of metal, preferably, and side flanges 24 are provided by means of which they are attached to and supported from the forward keel section 4 as indicated in dotted lines in 40 Fig. 4.

For lateral or surface steering of the appliance, a rudder 25 is utilized, the material and size and shape being such as best suited 45 for the purpose and the rudder is attached by its stem 26 to the tiller 27, which latter, is a transversely arranged bar, pivoted at 28 on the rudder post 29 which is passed through a selected hole 29', passing vertically through the keel board and through the keel section 3. There are a number of 50 these openings 29', the series extending fore and aft astern of the deck board, and the tiller post may be located in any one of these 55 holes to best adapt the steering to the length of the legs of the swimmer, or adjusted to suit his convenience.

At the ends of the tiller are located stirrups or loops 30, made of bent metallic rods 60 with their outer ends fitted in sockets in the extremities of the tiller and their inner ends 31 bent to pass transversely through the horizontal slots 32 in the tiller, and each end 31, which is threaded, is provided with a 65 clamp nut 33 so that the stirrups may be

moved toward or away from the tiller post or swivel point 28 of the tiller, and secured in adjusted position by the clamp nuts. It will readily be apparent that, with the toes and forefoot stuck down through the stirrups and the ball of the foot pressing against the front face of the tiller, the latter may be turned on its post to steer the appliance in well known manner.

For descending below or rising to the surface of the water, a fore rudder 34 and an aft rudder 35 are employed, these rudders, in the form of a horizontally disposed blade or vane, being hinged at 36 on the keel board 1 at its bow and stern, and connected by rods 37 and 38 on top of the keel board, extending beneath the deck board and pivotally attached to the hand levers 39 and 40 respectively. These levers are hinged or pivoted at 41 on the keel board, and extend 80 out beyond the sides of the keel board where they are in convenient position to be manipulated by the hands of the swimmer, and they may be held in adjusted position by engagement with the rack plates 42, one for 85 each lever attached at the sides of the deck board. In Fig. 1 the movement of these two vertically moving rudders or planes is indicated in dotted lines, and they may readily be adjusted manually by manipulation 90 of the handle levers 39 and 40 and the connecting rods 37 and 38. Outrigging or bow and stern guards 43 and 44 respectively, are provided to prevent fouling of the appliance and to protect the operating parts by 95 fending off approaching objects, the outrigging or fenders being arranged laterally of the appliance as well as beneath it.

From the above description taken in connection with my drawings it is evident that 105 the appliance may be propelled and steered by the swimmer, while in a swimmer's posture, and that the appliance may be steered both laterally and vertically and made to maneuver as desired, by hand and foot, while 110 being propelled by hand power.

What I claim is—

1. In a swimming appliance, the combination with manually operated propelling means, of a stern rudder for lateral steering including a fixed stem and transversely arranged tiller, means on the tiller for engagement by the feet of the swimmer, and hand operated bow and stern rudders for 115 steering the appliance in vertical planes.

2. The combination with the keel board and keel sections, the deck board and adjustable braces on the deckboard between which the swimmer may sit astride, propelling means for the appliance, and steering means for the appliance, as described.

3. The combination with the propelled appliance including its keel board and keel section having a series of openings therethrough, of a transversely disposed tiller 130

having its post passed through a selected one of said openings, foot stirrups at the ends of said tiller, and a rudder affixed to the tiller as described.

5 4. The combination with the long keel board and the fore and aft keel sections attached at the underside thereof, of a shorter deck board having a central longitudinal slot, a pair of transversely arranged braces

having supporting bolts passed through 10 said slot and adjustable therein whereby the swimmer may straddle the deck board between said braces, and manually operable means for propelling and steering the appliance. 15

In testimony whereof I affix my signature.

GEORGE W. BECHTEL.
